UNITED STATES PATENT OFFICE

172,405

CLOCK

Walter Paul Suter, Chicago, Ill., assignor to Jefferson Electric Company, Bellwood, Ill., a corporation of Illinois

Application December 28, 1953, Serial No. 28,220

Term of patent 14 years

(Cl. D42—7)

To all whom it may concern:

Be it known that I, Walter Paul Suter, a citizen of the United States, residing at Chicago, State of Illinois, have invented a new, original, and ornamental Design for a Clock, of which the following is a specification, reference being had to the accompanying drawings, forming a part thereof.

Fig. 1 is a front elevation of a clock showing my design;

Fig. 2 is a top view thereof;

Fig. 3 is a side elevation thereof, the oppo-

site side being substantially the same in appearance thereto; and

Fig. 4 is a rear elevation thereof.

I claim:

The ornamental design for a clock, as shown.
